UNITED STATES PATENT OFFICE.

REX H. NEWTON, OF WILKINSBURG, PENNSYLVANIA, ASSIGNOR TO WESTINGHOUSE ELECTRIC & MANUFACTURING COMPANY, A CORPORATION OF PENNSYLVANIA.

INSULATING WASHER FOR BRUSH-HOLDER BRACKET ARMS.

Application filed September 26, 1925. Serial No. 58,813.

My present invention relates to improvements in supporting means for brush-holder bracket arms, such as are utilized in dynamo-electric machines.

It has been the usual practice to mount the brush-holder bracket arms on an insulating ring extending around the entire circumference, in spaced relation to the commutator or slip ring with which the brushes co-operate. In certain instances, the use of an insulating ring has been avoided by mounting the brush-holder bracket arms directly upon a metallic portion of the stator frame and insulated therefrom by means of 15 large, flat insulating washers back of the bracket arms.

The utilization of an insulating supporting ring is objectionable on account of its higher cost and its susceptibility to breakage, resulting in frequent delays in repairing, which are brought about by the necessity for disconnecting all of the bracket arms when a new insulating supporting ring is inserted. The utilization of the second-mentioned construction, having large, flat insulating washers, is subject to the disadvantage that the dirt-laden air, blown around by the rotating current-collecting device, soon deposits a film of oily conducting particles covering all exposed surfaces and eventually resulting in a flashover between a brush-holder supporting arm and the metallic frame member, the arc discharging across the surface of the flat insulating washers.

The object of the present invention is to avoid the disadvantages of the prior constructions just mentioned, by the utilization of cupped insulating washers having flange portions extending outwardly from the metallic supporting member of the stator frame. My new construction is cheaper than the large circumferential insulating members heretofore used. Moreover, it provides insulation which is superior to that obtained either with the insulating supporting ring or with the large, flat insulating washers of the prior art, since the outwardly-disposed flanges of my cup-shaped insulating washers provide an increased creepage surface which is effective on both sides of the insulating member.

That is, if the windage of the machine causes the sides of the insulator flanges, which are exposed to the clockwise rotational

air currents, to become coated with oil, the other surface of the outwardly-extending flanges will still be available for furnishing the necessary protection. In this way, a much better result can be obtained and, in 60 the case of difficulty, replacement is easy and inexpensive.

It has been found, also, that the material of which my improved washer is made has a very definite bearing on its efficiency. A 65 smooth surface, to prevent dirt-accumulation, and a material that will not become carbonized, are both essential characteristics of such washers. In the accompanying drawing,

Figure 1 is a perspective view showing the direct-current side of a rotary converter embodying my invention, and

Fig. 2 is a perspective view of one of the insulating washers detached.

As shown in Fig. 1, the current-collecting device 1 is engaged by a plurality of brushes 2 which are supported by individual supporting arms or brackets 3 of conducting material. The brush-holder bracket arms 3 are carried by, and insulated from, a metallic ring 4 which is a part of the stator frame 5. Disposed between the bracket-supporting frame-portions 4 and each bracket arm 3 is one of my improved dished 80 insulating washers 7, which is illustrated more clearly in Fig. 2.

The insulating washer comprises a flat base portion 8 surrounded, on all four sides, by flanges or outwardly-extending portions 9, whereby the creepage distance is increased by causing the creepage to occur on both sides of the flanges, whereas, in the flat washer construction, the creepage is only over the outer or exposed surface of the 90 portion of the washer which projects beyond the base of the bracket arm. Also, in the use of my invention, the creepage resistance is greatly increased by reason of the fact that, regardless of the direction of rotation, at least one of the surfaces of the outwardly-extending flanges will be protected from exposure to the blast of dirt-laden air which is carried around by the rotating current-collecting device, and hence, one 95 clean insulator surface is always available to interrupt any possible creepage path.

My novel insulating washer herein described has been thoroughly tested in actual practice and has been found to be a very 110

remarkable improvement upon all types of air currents produced by the rotation of insulating mountings for the brush-holder supporting arms of large, high-voltage machines.

5 I claim as my invention:

1. The combination with a rotating current-collecting device, a co-operating brush, a brush-holder for said brush and a bracket arm of conducting material for supporting 10 said brush-holder, of a conducting frame member to which said bracket arm is insulatingly attached, and means for preventing the formation of a continuous film of oily conducting material joining said 15 frame member and said bracket arm, said means comprising a dished insulating washer disposed between said bracket arm and said frame-member and having flanges extending outwardly away from said frame- 20 member across the direction of flow of the

air currents produced by the rotation of said current-collecting device, whereby the conducting film of deposited dirt is interrupted by an insulating surface which is protected from the dirt-laden air currents. 25

2. The combination with a rotating current-collecting device, of a plurality of stationary brushes disposed there-around, brush-holder brackets for said brushes, an annular supporting member for said 30 brackets, and insulating means including baffle flanges extending outwardly away from said supporting member for providing an insulating surface, which is protected from the windage of the rotating device, in 35 the leakage path from each bracket.

In testimony whereof, I have hereunto subscribed my name this 20th day of August, 1925.

REX H. NEWTON.
